UNITED STATES PATENT OFFICE.

SIDNEY FITZHUGH MIOTON, OF NEW ORLEANS, LOUISIANA, ASSIGNEE OF TWO-FIFTHS TO JOSEPH OURY, OF NEW ORLEANS, LOUISIANA.

CONTROLLER FOR GAS-STOVES.

1,093,872.

Specification of Letters Patent.

Patented Apr. 21, 1914.

Application filed May 2, 1913. Serial No. 765,102.

To all whom it may concern:

Be it known that I, SIDNEY FITZHUGH MIOTON, a citizen of the United States of America, residing at New Orleans, in the 5 parish of Orleans and State of Louisiana, have invented certain new and useful Improvements in Controllers for Gas-Stoves, of which the following is a specification.

This invention relates to certain new and 10 useful improvements in controllers for gas burners, and relates particularly to that type of controller or regulator which is adapted to be applied to the burner of a gas or vapor stove, and which is operated through the 15 medium of a vessel placed over the burner of such stove.

The invention has for its primary object 20 to provide a controller of the above type which can be readily attached to any of the usual or ordinary gas stoves without necessitating any alteration of any of the parts of such stove.

The invention has for its further object to 25 provide a device of the character described preferably so constructed that it may readily be adjusted to conform to different sized stoves.

A still further object of the invention is to 30 provide a device of this type of extremely simple construction, which will not require the use of any special tools to apply the same to the burner, and which will be effective in use, and comparatively inexpensive to manufacture.

35 With the above and other objects in view, the invention resides in the novel construction, combination and arrangement of parts, as will be hereinafter more fully described and then claimed, and in describing the invention in detail, reference will be had to the accompanying drawings forming a part of this specification, and wherein like numerals of reference will be employed to designate like parts throughout different views in 40 which:

Figure 1 is a top plan view of a plurality of gas controllers constructed in accordance with the invention, the same being shown applied to the burners of a gas stove, the latter being indicated in dotted lines. Fig. 2 is a side elevation of the controller applied to the burner of a gas stove, the burner being shown in dotted lines. Fig. 3 is a front or end elevation of the controller, one of the 45 nipples of the valve casing being in cross

section. Fig. 4 is a longitudinal sectional view through the valve casing of the controller taken on the line 4-4 of Fig. 3. Fig. 5 is a detail view in side elevation of a modified form of operating lever. Fig. 6 is a detached detail view in side elevation of the controlling valve, and, Figs. 7, 8, and 9 show modified forms of supporting clip or bracket.

It is common in all types of gas or vapor stoves to employ a mixing tube which is located between the shut-off valve and the burner proper, and the present device is adapted to be readily attached to such mixing tube, and in connection therewith there is provided a controlling valve adapted to 60 be operated by the mechanism hereinafter described.

In the accompanying illustration, 10 indicates the mixing tube of an ordinary gas stove which communicates with the burner 75 11, and is provided at its outer end with an air mixer 12, the controlling valve being located between the mixer 12 and the supply line 14.

To apply the device, it is only necessary 80 to remove the controlling valves on the supply line 14 and substitute therefor the controlling valve shown in detail in Figs. 4 and 6. This consists of a valve casing 15 having a nipple 16 for connection with the air mixer 85 12 and a nipple 17 for connection with the supply line 14. In this casing is a plug valve 18 provided with a suitable handle 19, and which plug valve has the usual transverse port 20. In addition to said port 20 90 the valve is provided with a feed groove 21 which communicates with a by-pass pipe 22 that is carried inwardly to the burner and terminates in a pilot light 23 which may be of any suitable form, and which is disposed 95 so as to ignite the gas at the burner 11.

The valve casing 15 is provided with a valve seat 24 extending transversely through the casing at right angles to the valve 18, and in said seat is a plug or other form of 100 rotary valve 25 which has a transverse port 26. The stem of this valve projects to one side of the valve casing 15 and has suitably connected thereto one end of a link 27, the other end of which has a pin 28 to work in 105 a slot 29 provided therefor in the operating lever 30. This operating lever is pivotally supported at 31 from a clip or bracket 32 which is hung on the mixing tube 10 and suitably secured in any desired manner by a 110

set screw 33. The clip shown in the drawing is especially adapted for use in connection with the pivoted lever 30, being provided at one end with a curved arm 30^a to 5 embrace the tube 10 upon which it is adjustably secured by the set screw 33, and at its opposite end with parallel ears 30^b between which the lever 30 is pivoted, as best shown in Figs. 7, 8, and 9. The lever comprises 10 two sections, consisting of the main section 30 and a supplemental or outer section 34 which is adjustably connected at 35 by a set screw and slot with the outer end of lever 30. The making of this lever in two sections 15 is for the purpose of providing a quick adjustment to adapt the device to different sized stoves.

The lever at the outer end thereof is bent upwardly as best seen at 36 in Fig. 2 so that 20 its free end will normally lie slightly above the plane of the burner 11, and this end may, if desired, be provided with a tripod 37 as shown in Fig. 5 of the drawings. The lever is held so that its free extremity will be 25 normally in the above described position by means of a counter-weight 38 placed on the lever between the securing bracket 32 and the inner end of said lever, or in other words at a point back of the pivot 31.

30 In Figs. 7, 8, and 9, modified forms of the bracket for supporting the mixing tube are shown. In Fig. 7 the bracket 32' is exhibited as of J-form, in Fig. 8, as of curvilinear rectangular form, and in Fig. 9, as of right-35 angled curvilinear contour. Either of these brackets will be effective for maintaining the mixing tube in operative position and may be substituted for that shown in Fig. 1.

With reference to the drawings, the device 40 is shown in Fig. 2 with the gas shut off, and the operating lever in its normal position. When it is desired to use the stove, the valve 18 is turned by its handle 19 so as to allow the gas to pass from the supply pipe 14 45 through feed groove 21 and by-pass pipe 22 to the pilot light where it may be ignited. Upon placing a utensil over the burner 11, the end 36 of the lever is depressed by the

weight of such utensil, thus operating the link 27, opening valve 25, and turning the 50 gas into the mixing tube 10 through which it passes to the burner 11 and is ignited by the pilot light. Obviously, further control of the gas may be had by proper manipulation of the valve 18. As soon as the utensil 55 is moved from the burner, the counter-weight 38 acts on the lever 30 so as to close valve 25, shutting off the flow of gas to the burner, but leaving the flow of gas through by-pass pipe 22 to the pilot light uninterrupted until the valve 18 is closed by hand. 60

Particular attention is called to the fact that the device as shown and described may be readily attached to any of the ordinary forms of gas or vapor stoves, the application necessitating simply the removal of the usual valves found in the supply line 14 and the substitution therefor of the valve herein shown and described. 65

I claim:—

An attachment for gas ranges comprising a bracket secured to the gas feed pipe and having a curved arm and parallel ears, a slotted lever pivoted between said ears, a counter-weight carried by the lever, the inner end of said lever having a longitudinally adjustable extension, said extension having an upturned terminal arranged to be disposed within a burner, a link having a pin projecting therefrom and entering the 70 slot in the weighted end of the lever, a valve slot in the weighted end of the lever, a valve casing, a vertically-disposed shut-off valve therein provided with a curved feed groove, a by-pass communicating with the groove, and a horizontally-disposed controlling 75 valve in said casing projecting at one side of the valve casing and having the other end of the link connected thereto for controlling the movement of the valve. 80

In testimony whereof I affix my signature 85 in presence of two witnesses.

SIDNEY FITZHUGH MIOTON.
